UNITED STATES PATENT OFFICE.

DAVID S. BUTLER, OF BROWNSVILLE, MISSOURI.

IMPROVEMENT IN BRIDLE-BUCKLES.

Specification forming part of Letters Patent No. 123,866, dated February 20, 1872.

To all whom it may concern:

Be it known that I, D. S. BUTLER, of Browns-
ville, in the county of Saline and State of
Missouri, have invented a new and valuable
Improvement in Bridle-Buckles; and I do
hereby declare that the following is a full, clear,
and exact description of the construction and
operation of the same, reference being had to
the annexed drawing making a part of this
specification, and to the letters and figures of
reference marked thereon.

Figure 1 of the drawing is a representation
of a longitudinal section of my invention. Fig.
2 is a back view of the same.

This invention has relation to self-fastening
bridle-buckles; and consists in the construction
and novel arrangement of a hinged curved
plate having a pin or tongue to fasten the
strap, as hereinafter described, the object be-
ing to provide an improved bridle or halter
buckle, to which a strap or straps may be
readily and securely attached without the ne-
cessity of stitching or riveting.

In the accompanying drawing, A represents
a flat or, preferably, a slightly-curved buckle-
frame, having its convex side downward. This
buckle-frame is provided with the projecting
transverse bar B, located midway between its
ends. C indicates a longitudinally-convex plate,
whose curvature is tangent, or nearly so, with
the curvature of the frame A. This plate is
constructed with a pair of bent jaws or lugs,
d, which grasp the rounded bar B and form a
hinge, by means of which the plate C is al-

lowed to turn, so that the straps may be more
easily inserted, and be allowed to move so as
to correspond to the motions of the horse.
From the center of the plate C a pin, d',
projects, and is designed for the purpose of fast-
ening the strap or straps, which are perforat-
ed in the usual manner. The plate C, as con-
structed, constitutes a support to keep the
straps securely in place, and being curved does
not tend to cut or injure the straps, while the
reverse curvature of the frame serves to bring
the angular edge of its end bar sharply against
the strap, thus tending to hold it securely.
At the same time the pin is shortened up and
brought into the plane connecting the ends of
the buckle-frame, so that the strap will be
forced down toward its base. By the use of
the bent plate, the strap is carried somewhat
out of the direct line of draft, and is thereby
rendered more secure in the buckle.

I claim as my invention—

The buckle herein described, consisting of
the quadrangular concave frame A and the
convex segment-plate C, centrally pivoted on
the bar B, and provided with center pin d'
and bent lugs d, substantially as specified.

In testimony that I claim the above I have
hereunto subscribed my name in the presence
of two witnesses.

DAVID SPOTSWOOD BUTLER.
